UNITED STATES PATENT OFFICE

PAUL BETZLER, OF JACKSON, NEW YORK

INTERLOCKING-UNIT CONSTRUCTION

Application filed June 27, 1929. Serial No. 373,966.

This invention relates to building construction and more particularly refers to improvements in building units of the interlocking type adapted to considerably reduce the cost 5 of buildings of various descriptions.

The primary object of this invention is to provide a building unit of a novel and improved design comprising a relatively thin web body and two flanges inwardly extending therefrom, one of said flanges being in the form of a rib and the other one having a hook formed section adapted to interlock with the rib of an adjoining unit so as to form therewith a beam or column member as the 15 case may be.

Another object is to provide a building unit or slab of the character specified made of preferably reinforced cementitious material, said unit being cast with openings through 20 said rib and beam or column member, permitting the insertion of binding bars connecting adjoining units together.

A further object is to provide a building unit or slab of the character specified provided with means such as a furring strip forming a foundation onto which lathing or building boards or other similar materials may be easily secured.

A still further object is to provide a construction composed of a plurality of elements or units preferably formed of reinforced concrete or other cementitious material, said units being interlocking with one another and being held together to form a complete structure by means of suitable reinforcing and binding elements cooperating therewith.

Other objects and advantages of the present invention will more fully appear as the description proceeds and will be set forth and claimed in the appended claims.

My invention is illustrated in the accompanying drawings, in which:

Fig. 1 is a view in perspective of a building unit or slab embodying my invention;

Fig. 2 is a fragmentary view in perspective partly sectioned of a corner of a building in which building slabs of the type shown in Fig. 1 are employed for the construction 50 of its walls;

Fig. 3 is a fragmentary elevation of one of the walls of said building;

Fig. 4 is a plan sectional view thereof;

Fig. 5 is a fragmentary cross sectional view of the same; and

Fig. 6 is a partial view in perspective of a floor formed of a plurality of building units of the same type.

In the construction of buildings of various descriptions, it is desirable to reduce the cost 55 of labor as well as the weight of the various structures without however, impairing their stability or strength.

The building slab or unit to which this invention more particularly refers is of an 60 extremely light weight and by virtue of its peculiar design makes it possible to build walls or floors of great strength with the expenditure of a comparatively limited amount of labor.

Referring to Fig. 1, it will be observed that my improved slab or unit comprises a web body 10 having one of its longitudinal edges 11 bent inwardly preferably at right angle to said body to form a rib 12. The other longitudinal edge 13 is also bent inwardly as shown at 14 then laterally as shown at 15 and then outwardly as shown at 16, so as to form a hook sectioned member which in use will constitute a part of a column or beam according to whether the slab is used for the construction of a wall or a floor.

The free edge 17 of outer wall 16 of the beam or column member is spaced a distance a , from the plane of the outer surface of the 75 web body, the distance a , substantially corresponding to the thickness of said web body.

The distance b between the plane of the outer surface of the web body and the bottom 18 of the groove 19 formed by the three 80 walls of the column or beam member is substantially equivalent to or slightly greater than the width b' of rib 12.

As a result of this construction, the rib portion of one unit may be inserted within 85 the groove formed by the column or beam member of an adjoining unit so as to interlock therewith.

Rib 12 and groove 19 are preferably so shaped that the rib of one unit may be in- 90 100

serted within the groove of an adjoining unit in a transverse direction to the plane of web body 10, in order to facilitate and speed up building operations.

5 A wall can thus be built as shown in Figs. 3, 4, comprising a plurality of interlocking units 20, 21, etc., the outer surfaces of their web bodies 20', 21', forming a continuous surface which is the outer surface of the wall.

10 Horizontal binding bars such as 22 can be inserted as the work progresses alongside the inner surface of the wall through perforations 23, 24, 23', 24' provided through ribs 12 and walls 14, 16 of the column or beam members as shown in Fig. 1.

15 Interlocking slabs or units of the type just described can be made of sheet metal if desired, but for the majority of purposes, I prefer to make them out of plastic compositions which may be selected according to the use for which the slabs or units are intended. For instance for the construction of light partition walls the slabs can be made in the form of plaster boards while for the construction of outer and main walls, they are preferably made of reinforced concrete as shown in Fig. 4.

20 In this case, each slab or unit is provided with reinforcing members, which may be suitably placed longitudinal bars 25, 26, etc., connected by transversal wire or screen members 27. Openings 23, 24, 23', 24', can be pre-cast in the slabs, as will be understood.

25 When the slabs are made out of cementitious materials or other plastic compositions the groove 19 of each column member is made somewhat wider and deeper than rib 12 so as to leave a small clearance space such as indicated at 28 in Fig. 4 between their adjoining surfaces.

30 This clearance space permits the insertion of mortar or cement which will form a strong and positively water proof binding between adjoining units. The slabs are preferably made sufficiently long to extend from floor to floor. The foundation wall 29 shown in Fig. 2 preferably has its upper surface formed with a horizontal groove 30 running all along the wall, the width of said groove substantially corresponding to the distance between the outer surface of the slab and the inner surface of the column members.

35 After the wall of the first floor has been built and binding bars 10 have been placed in position as shown in Fig. 2, a suitable frame work is placed in position so as to cast horizontal beam members 31 running between adjoining column members at the upper end of the slabs.

40 After this is done the construction of the next story can be started, the slabs composing the upper wall being anchored or positioned at the base in any suitable manner.

45 No definite rules can be given as to the manner of inter-connecting the elements com-

posing the various floors, because the procedure to be followed in these operations is to be determined by the architect according to the type of construction to be produced.

50 For instance, if the building has a steel frame the slabs will be attached to the frame and the slabs of one story need not be interconnected with the slabs of an adjoining story.

55 When windows have to be provided as shown at 32 in Figs. 3 and 4, wider than the width of a slab, the wall underneath the window sill may be formed by cutting the slab or slabs so as to support the window sill 33 at the proper distance from the floor, while the window enclosure may be completed at the top by providing a horizontal member 34 extending between the two column members between which the window is inserted.

60 A corner formed by two walls constructed in the manner described is preferably completed by means of a special slab or unit such as shown at 35 in Figs. 2 and 4; the two end slabs of 36, 37 of the two walls are made to abut at right angle to each other along the outer corner edges of their respective column members.

65 The corner unit or slab 35 comprises two web sections 38, 39 at right angle to each other, and two rib sections 40, 41 bent inwardly at right angle thereto from the edges thereof, said rib sections being adapted to interlock with the column members of slabs 36, 37.

70 A vertical square chamber 42 will therefore be formed by the outer surfaces of the two column members and by the inner surfaces of web sections 38, 39. Said chamber is preferably filled with concrete as the building progresses as shown at 43, forming a solid corner column which is preferably reinforced all through by a vertical reinforcing member 44.

75 When the slabs are made of reinforced concrete or other cementitious material the outer surface of the web body is preferably provided with means such as a furring strip 45 adapted to form a foundation onto which lathing or composition boards or like materials can be easily nailed as shown at 46. The slab is preferably built in unit form with the furring strip which may be anchored within the concrete in any suitable manner.

80 It is also possible, of course, when pouring the concrete to form the upper wall beam 47 shown in Fig. 5, to insert anchoring bolts 48 which will project upwardly therefrom, providing means for securing a wooden strip 49 onto which the roof rafters 50 can be secured in any suitable manner.

85 The building units or slabs constructed according to my invention can also be used for building floors, as shown in Fig. 6, where 51 designates a floor composed of a plurality of interlocking units 52, 53, 54, etc., horizontally

arranged, the web portions of said slats forming the floor foundation proper and the interlocking members forming the beams.

Said beams are preferably provided with 5 furring strips 55 onto which lathing or composition boards 56 can be attached.

The rib and beam or column members need not necessarily be directed at 90° to the surface of the web body, although it is preferable that they be at right angle to said surface as shown.

Other minor details of the invention may vary from those shown without departing from the inventive idea; the drawings will 15 therefore be understood as being intended for illustrative purposes only and not in a limiting sense. Accordingly I reserve the right to carry my invention into practice in all those ways and manners which may enter, 20 fairly, into the scope of the appended claims.

I claim:

1. A building unit of the character specified, including a web body having one of its longitudinal edges inwardly bent at an angle 25 to the surface of said body, to form a rib integral therewith, and having its other longitudinal edge bent inwardly, laterally and outwardly to form a hook sectioned beam or column member, the groove formed by the 30 hook section thereof being wide enough to permit the insertion of a rib similar to that integral with the opposite edge of said unit, in a direction transversal of the surface of said web body.

35 2. A building unit of the character specified, including a web body having one of its longitudinal edges inwardly bent at an angle to the surface of said body, to form a rib integral therewith, and having its other longitudinal edge bent inwardly, laterally and outwardly to form a hook sectioned beam or column member, the groove formed by the 40 hook section thereof being wide enough to permit the insertion of a rib similar to that integral with the opposite edge of said unit, in a direction transversal of the surface of said web body, the outwardly directed portion of said member having its free edge spaced from the plane of the outer surface 45 of said web body a distance substantially corresponding to the thickness of said web body, and the bottom of said groove being spaced from said outer surface a distance substantially corresponding to the distance from the 50 edge of said rib to said outer surface.

55 3. A building unit of the character specified, including a web body having one of its longitudinal edges inwardly bent at an angle to the surface of said body, to form a rib integral therewith, and having its other longitudinal edge bent inwardly, laterally and outwardly to form a hook sectioned beam or column member adapted to interlock with the rib member of an adjoining similar unit, said rib and member being provided with

aligned openings permitting the insertion of binding bars therethrough.

4. A building unit of the character specified, including a web body having one of its longitudinal edges inwardly bent at an angle to the surface of said body, to form a rib integral therewith, and having its other longitudinal edge bent inwardly, laterally and outwardly to form a hook sectioned beam or column member, the groove formed by the hook section thereof being wide enough to permit the insertion of a rib similar to that integral with the opposite edge of said unit, in a direction transversal of the surface of said web body, said rib and member being 70 provided with aligned openings permitting the insertion of binding bars therethrough.

5. A construction of the character described, comprising a plurality of units, each unit including a web body having one of its longitudinal edges inwardly bent at an angle to the surface of said body, to form a rib integral therewith, and having its other longitudinal edge bent inwardly, laterally and outwardly to form a hook sectioned beam or column member, the rib of one unit being 80 insertable within the groove formed within the beam or column member of an adjoining unit, so as to form an interlocking joint therewith, and binding bars running through said 85 interlocking ribs and members, along a direction parallel to the outer surface formed by the web bodies of said units.

6. In a construction of the character described, a corner comprising two units arranged at right angle to each other, each unit including a web body having one of its longitudinal edges bent at right angle inwardly, laterally and outwardly so as to form a hook sectioned column member, the outer corner edge of one of said column members abutting against the outer corner edge of the other, and a corner locking member comprising a web body portion having a right angled section, and a rib inwardly bent at right angle to the surface of said body portion at each longitudinal edge thereof, said ribs being insertable within, and being adapted to interlock with the column member of the adjoining units.

7. In a construction of the character described, a corner comprising two units arranged at right angle to each other, each unit including a web body having one of its longitudinal edges bent at right angle inwardly, laterally and outwardly so as to form a hook sectioned column member, the outer corner edge of one of said column members abutting against the outer corner edge of the other, a corner locking member comprising a web body portion having a right angled section, and a rib inwardly bent at right angle to the surface of said body portion at each longitudinal edge thereof, said ribs being insertable within, and being adapted to interlock 125

with the column member of the adjoining units, and binding bars running through said interlocking ribs and members.

8. In a construction of the character described, a corner comprising two units arranged at right angle to each other, each unit including a web body having one of its longitudinal edges bent at right angle inwardly, laterally and outwardly so as to form a hook sectioned column member, and outer corner edge of one of said column members abutting against the outer corner edge of the other, a corner locking member comprising a web body portion having a right angled section, and a rib inwardly bent at right angle to the surface of said body portion at each longitudinal edge thereof, said ribs being insertable within, and being adapted to interlock with the column member of the adjoining units, binding bars running through said interlocking ribs and members, and a body of cementitious material filling the chamber formed by the side surfaces of said column members and by the inner surfaces of said corner locking member.

9. In a construction of the character described, two walls at right angle to each other, each wall comprising a plurality of units, each unit including a web body having one of its longitudinal edges inwardly bent at an angle to the surface of said body, to form a rib integral therewith, and having its other longitudinal edge bent inwardly, laterally and outwardly to form a hook sectioned column member, the rib of one unit being insertable within the groove formed within the column member of an adjoining unit, in a direction transversal of the surface of said web body, so as to form an interlocking joint therewith, the end units of said two walls being arranged at right angle to each other and having the outer corner edges of their respective column members abutting against each other, and a corner locking member comprising a web body portion having a right angled section, and a rib inwardly bent at right angle to the surface of said body portion at each longitudinal edge thereof, said ribs being insertable within, and being adapted to interlock with the column member of the adjoining units.

10. In a construction of the character described, two walls at right angle to each other, each wall comprising a plurality of units, each unit including a web body having one of its longitudinal edges inwardly bent at an angle to the surface of said body, to form a rib integral therewith, and having its other longitudinal edge bent inwardly, laterally and outwardly to form a hook sectioned column member, the rib of one unit being insertable within the groove formed within the column member of an adjoining unit, in a direction transversal of the surface of said web body, so as to form an interlocking joint therewith, the end units of said two walls being arranged at right angle to each other and having the outer corner edges of their respective column members abutting against each other, a corner locking member comprising a web body portion having a right angled section, and a rib inwardly bent at right angle to the surface of said body portion at each longitudinal edge thereof, said ribs being insertable within, and being adapted to interlock with the column member of the adjoining units, and binding bars running through said interlocking ribs and members.

ing joint therewith, the end units of said two walls being arranged at right angle to each other and having the outer corner edges of their respective column members abutting against each other, a corner locking member comprising a web body portion having a right angled section, and a rib inwardly bent at right angle to the surface of said body portion at each longitudinal edge thereof, said ribs being insertable within, and being adapted to interlock with the column member of the adjoining units, and binding bars running through said interlocking ribs and members.

CERTIFICATE OF CORRECTION.

Patent No. 1,757,763.

Granted May 6, 1930, to

PAUL BETZLER.

It is hereby certified that error appears in the above numbered patent requiring correction as follows: In the grant and in the heading to the printed specification the residence of the patentee is erroneously given as "Jackson, New York", whereas said residence should have been given as "Jackson Heights, New York"; and that the said Letters Patent should be read with this correction therein that the same may conform to the record of the case in the Patent Office.

Signed and sealed this 24th day of June, A. D. 1930.

(Seal)

M. J. Moore,
Acting Commissioner of Patents.
